United States Patent

Des. 242,494

Patented Nov. 23, 1976

242,494

HAIR DRYER OR SIMILAR ARTICLE

John C. Shalvoy, Fairfield, Conn., assignor to
General Electric Company, Bridgeport, Conn.

Filed Feb. 19, 1974, Ser. No. 443,446

Term of patent 3½ years

Int. Cl. D28—03

U.S. Cl. D86—10 F

Published under the second Trial Voluntary Protest
Program on Apr. 6, 1976, as document No. B443,446

FIG. 1.

FIG. 2.

FIG. 3.

FIG. 4.

FIG. 5.

FIG. 6.

FIG. 7.

FIG. 1 is a perspective view of a hair dryer or similar article showing my new design;

FIG. 2 is a top plan view thereof;

FIG. 3 is a bottom plan view thereof;

FIG. 4 is a rear elevational view thereof;

FIG. 5 is a front elevational view thereof;

FIG. 6 is a left end elevational view thereof; and

FIG. 7 is a right end elevational view thereof.

I claim:

The ornamental design for a hair dryer or similar article, substantially as shown.
